CIRCULAR DEPOSITORY

Edward W. Kenyon, Detroit, Mich.

Application April 15, 1935, Serial No. 16,517

1 Claim. (Cl. 232—17)

This invention relates to a depository or collection box for dwellings or the like, and has for the primary object the provision of a device of this character in which circulars and bills may be placed when delivered to a dwelling to prevent loss thereof and is so constructed that the bills and circulars will be kept separated and may be conveniently obtained without the danger of them falling out of the device when the latter is being opened.

With these and other objects in view, this invention consists in certain novel features of construction, combination and arrangement of parts to be hereinafter more fully described and claimed.

For a complete understanding of my invention, reference is to be had to the following description and accompanying drawing, in which Figure 1 is a perspective view illustrating a depository or collection box constructed in accordance with my invention.

Figure 2 is a sectional view taken on the line 2—2 of Figure 1.

Figure 3 is a sectional view taken on the line 25 3—3 of Figure 2.

Referring in detail to the drawing, the numeral 1 indicates a casing of considerable length and is adapted to be arranged upon a support in a vertical position. The side walls of the casing 1 at the lower end of the latter are of a greater length than the front and rear walls and a bottom 2 is hinged to the lower edge of the rear wall while the opposite edge of the bottom is detachably secured to the front wall by a catch 3. The bottom wall 2 is arcuately curved and the edges of the side walls of the casing are correspondingly curved so as to conform to the bottom when the latter is positioned to close the lower end of the casing.

40 A top wall 4 is secured in the upper end of the casing and has slots 5 and 6. Suitably secured to the top wall and depending in the casing is a flexible partition 7 dividing said casing into compartments 8 and 9, the slots 6 being disposed

over the compartment 8 while the slot 5 is disposed over the compartment 9.

The casing is normally closed by a cover 10 hinged to the rear wall, as shown at 11. The top face of the cover, adjacent the front edge, has the word "Bills" applied thereto indicating that such should be deposited in the casing by way of the slots 6. An upstanding plate 12 is carried by the cover 10 and has applied thereto the word "Circular" indicating that such should be deposited in the compartment 8 by way of the slot 5, the latter being of a larger size than the slots 6 due to the fact that usually circulars are larger than bills. The front wall of the casing may have applied thereto words as follows: "No mail", 15 "Circulars" and "Bills only".

An upstanding plate 13 is secured to the bottom 2 and when the latter is in position to close the lower end of the casing said plate aligns with the partition 7. The purpose of the plate 13 is 20 to prevent the contents of the compartments 8 and 9 from falling out of the casing when the bottom is being moved towards an open position.

Any suitable means may be employed for securing the casing to the wall of a building or 25 some other part of said building, or if desired, the casing may be supported by a pedestal, post or like device resting in the ground.

Having described the invention, I claim:

A depository comprising a vertically arranged 30 casing, a curved bottom hinged to said casing for closing the lower end of the latter, a top wall located in the upper end of the casing and having spaced slots, a flexible partition carried by said top wall and dividing the casing into compartments, a hinged cover for closing the upper end of the casing and bearing instructions as to what matter to insert in said compartments by way of the slots, and a plate carried by the bottom to align with the partition when said bottom is located to close the casing and adapted to prevent the contents of the compartments from falling therefrom during the opening of said bottom.

EDWARD W. KENYON.
